UNITED STATES PATENT OFFICE.

DOMINGO A. PISTORIO, OF WASHINGTON, DISTRICT OF COLUMBIA.

PROJECTILE.

1,291,117.

Specification of Letters Patent. Patented Jan. 14, 1919.

Application filed November 13, 1915. Serial No. 61,223.

To all whom it may concern:

Be it known that I, DOMINGO A. PISTORIO, a citizen of the United States of America, and resident of Washington, in the District 5 of Columbia, have invented certain new and useful Improvements in Projectiles, of which the following is a specification.

This invention relates to projectiles and particularly to those projectiles having fuses 10 of the high explosive type, the said invention being directed to the provision of novel means for igniting the charge of the projectile on impact of the said projectile, the said fuse having novel means for retaining the 15 firing mechanism against movement during the flight of the projectile or while it is being handled at all times prior to its being fired.

A further object of this invention is to 20 provide novel means for producing concussion upon impact of the projectile for firing the high explosive charge, the same including, in one form of the invention, a cap or caps in position to be impinged by firing 25 pins and an explosive charge ignited by said caps, the same being associated with means for producing concussion effective to fire the high explosive charge.

A still further object of this invention is 30 to provide a fuse in which the hammer and the firing pin or pins carried thereby as well as the safety appliances and means for holding the said safety appliance or guard, are self contained by the hammer and carried thereby.

A still further object of this invention is 35 to provide a high explosive fuse of the character indicated which may be utilized in connection with a high explosive charge 40 solely or it may be used in connection with a high explosive charge and supplemental means for detonating the high explosive charge.

With the foregoing and other objects in 45 view, the invention consists in the details of construction, and in the arrangement and combination of parts to be hereinafter more fully set forth and claimed.

In describing the invention in detail, reference will be had to the accompanying

drawings forming part of this specification wherein like characters denote corresponding parts in the several views, and in which—

Figure 1 illustrates a longitudinal sectional view of a fuse embodying the invention;

Fig. 2 illustrates a sectional view on a line corresponding with the line 2—2 of Fig. 1;

Fig. 3 illustrates a sectional view on a line 60 corresponding with the line 3—3 of Fig. 2;

Fig. 4 illustrates a sectional view on a line corresponding with the line 4—4 of Fig. 2;

Fig. 5 illustrates a longitudinal sectional view of a modified construction;

Fig. 6 illustrates a sectional view on a line corresponding with the line 6—6 of Fig. 5;

Fig. 7 illustrates a sectional view on a line corresponding with the line 7—7 of Fig. 5;

Fig. 8 illustrates a sectional view on a line 70 corresponding with the line 8—8 of Fig. 5; and

Fig. 9 illustrates a fragment of the interior of the fuse.

In these drawings 10 denotes the body of 75 the fuse having external threads 11 which will permit it to be inserted in the base of a projectile. The interior of the body is provided with a chamber 12, the diameter of which varies so that there are formed shoulders for a purpose to be presently explained.

The extreme inner end of the chamber contains the hammer 13, the body of which is of such weight as to prove effective to carry the firing pins 14 against the caps 15 85 with such force as to cause an explosion of the caps. The hammer 13 has a transversely disposed channel 16 in which guards 17 are slid able, the said guards being of such weight as to be affected by centrifugal force, 90 so that they will be moved outwardly when the projectile is rapidly rotating in its flight, the purpose of the said guards being to release the spacing pin 18, the head 19 of which is in contact with the plug 20 of the 95 internal casing 21, which will be presently described.

The plug 20 has apertures 22 therein for the reception of the caps, as stated, and back of the said caps, the said apertures 22 are 100

provided with guiding collars 23 having apertures 24 in which firing pins 16 slide and are guided. The fact that the firing pins are secured in the guiding collars insures the rotation of the hammer under the influence of the rotation of the projectile, thus causing the guards to move outwardly under the influence of centrifugal force.

As a means for holding the guards normally inward in engagement with the shoulder of the head of the pin, the said guards have conical recesses 25 in which conical springs 26 are seated, the outer ends of the said conical springs bearing on a sleeve 27 which encircles the hammer near one end, the said sleeve being held by an end plate 28 secured to the end of the hammer.

The threaded shanks 29 of the firing pins are seated in threaded apertures 30 of the hammer and shoulders 31 on said firing pins serve to retain the end plate in position on the hammer.

The hammer is further provided with a channel 32 forming a clearance for the end of the guard pin so that when the head of the guard pin is released, the hammer may move over the guard pin to bring the firing pins into engagement with the caps.

The casing 21 is externally threaded at 33 to engage internal threads of the body of the fuse, and the casing, except where it is threaded, stands away from the internal wall of the fuse body so that there is a channel formed between the casing and the fuse body for the storage of a high explosive 34. The interior of the casing 21 is provided with a web having an aperture 36 so that the interior of the casing may be divided into compartments 37 and 38, the former of which 40 contains an explosive charge ignited by the flames from the caps when they are detonated. The chamber or compartment 38 has a ball 39 which bears against a follower 40, the said follower 40 having a plug 41 lying in the aperture 36 of the web and it is the purpose of the inventor that when the explosive charge in the chamber 37 is ignited, it shall be effective to force the ball outwardly into engagement with an expanding member 42 stationed in the chamber 38. The wall of the casing 21 is weakened by the longitudinally disposed grooves 43 and as the ball is forced over the inclined surfaces 44 of the said expanding member, the force will be sufficient to fracture the wall of the casing, causing concussion to ignite the high explosive charge. By this means, the applicant has provided the initial explosive charge which is ignited by the caps and the expanding means and, therefore, he has two agencies operating to fracture the wall of the casing 21 to insure the detonation of the high explosive charge. The expanding member 42, as shown, consists of a body, the in-

ner end of which has the inclined walls 44 65 and the said body has a longitudinally disposed slot 45 which serves to weaken the expanding member so that the ball may, to a great extent, prove effective for the purpose intended. In Figs. 1 and 2, there is shown a supplemental ball 46 which acts somewhat in the nature of a wedge for causing spreading of the expansion member. The casing 21 at its threaded portion has a transversely disposed threaded opening 47 for the reception of a screw 48, which screw is effective for holding the plug 20 against rotation under the influence of the rotating projectile.

The outer end of the casing 21 has a cap 49, which cap is threaded on the casing, and the outer end of the cap has a stud 50 seated in a recess 51 of the plug 52 threaded in the outer end of the fuse.

Seats or recesses for spanning wrenches or other means for turning the heads and plugs 85 are shown, but they need not be described in detail.

For the purpose of guarding against leakage, and insuring tight joints, disks 53, 54 and 55 are supplied, the said disks being 90 fracturable so that they do not interfere with the operation of the device as intended, but serve solely as guards for retaining the parts in position for increasing the efficiency of the joints between the several parts. 95

In that form of the invention shown in Figs. 5 to 8 inclusive, the hammer, guard, firing pins and spacing pin are preferably of the construction heretofore described and it is believed unnecessary to describe them 100 in detail in connection with a description of the modification, but for the purpose of identifying them in a general way, the firing pins are supplied with the reference character 56, and the spacing pin with 57. 105 The guards 58 are in the hammer 59 and may slide in the interior of the fuse body 60. The casing 61 in the modification is of the same general construction as the casing 21 and the only difference between this form 110 of the invention and that heretofore described, is that the chamber 62 of the casing has a container 63 for the reception of an acid which would prove effective to ignite the high explosive charge when the said acid is released and in this connection, means are provided for causing the puncture or fracture of the container to permit the escape of the acid upon impact of the projectile containing the fuse. Furthermore, in this 115 modification, the aperture of the web 64 has a bushing 65 threaded in it and the bushing has an aperture 66 with a projectile 67 therein, the said projectile having an aperture 68 therein for receiving the shearing pin 69 which shearing pin has its ends seated in apertures 70 in the said bushing. The projectile is, therefore, held against move-

ment by the shearing pin but it is intended that the force of the explosion of the contents of the chamber 71 shall be effective to cause the small projectile to break the shearing pin and pass into the receptacle containing the acid, so that the acid will find its way, as stated, to the high explosive charge and aid in its ignition, thus augmenting the effect of the explosive charge in the chamber 71.

10 The high explosive charge when exploded will rupture the wall or casing 61 and container 63 and the concussion will aid in detonating the explosive charge, whereas the acid will also aid in igniting the said charge.

In other respects, the modification is of the same general construction as the construction described in connection with the disclosure of the device illustrated in Figs.

20 1 to 4 inclusive.

It is believed unnecessary to here supply a résumé of the operation of the parts, since the parts have been described and their functions have been ascribed to them so that 25 one skilled in the art will, it is thought, understand the construction and operation of the device.

The member 39 has been referred to as a ball, but it is to be understood that any 30 member which will operate as a wedge in conjunction with the expanding member may be utilized in this connection.

I claim:

1. In a fuse, a fuse body having an internal bore, a hammer consisting of a body having a transversely disposed channel, guards 35 slideable therein, means for yieldingly pressing the guards toward the center of the hammer, a pin slideable in the hammer, means on the pin engaged by the guards for holding the said pin normally outward, firing pins carried by the hammer, a member against which the pin abuts for preventing movement of the hammer under 40 normal conditions, a casing within the body of the fuse, said casing having an explosive charge therein, caps in position to ignite the explosive charge and to be impinged by the firing pins, and a high explosive charge 45 surrounding the casing.

2. In a fuse, a fuse body having an internal bore, a hammer consisting of a body having a transversely disposed channel, guards slideable therein, means for yieldingly pressing the guards toward the center of the hammer, a pin slideable in the hammer, means on the pin engaged by the guards for holding the said pin normally outward, firing pins carried by the hammer, a member 55 against which the pin abuts for preventing movement of the hammer under normal conditions, a casing within the body of the fuse, said casing having an explosive charge therein, caps in position to ignite the explosive charge and to be im-

5 sive charge and to be impinged by the firing pins, a high explosive charge surrounding the casing, an expansible member within the casing, a member adapted to travel for expanding the said member, and means for imparting the force of the first mentioned explosive charge to the said means for expanding the member.

3. In a fuse, a body having an internal bore, a hammer consisting of a body having a transversely disposed channel, guards slideable therein, means for yieldingly pressing the guards toward the center of the hammer, a pin slideable in the hammer, means on the pin engaged by the guards for holding the said pin normally outward, firing pins carried by the hammer, a member against which the pin abuts for preventing movement of the hammer under normal conditions, a casing having its walls grooved for 70 weakening the said walls within the body of the fuse, said casing having an explosive charge therein, caps in position to ignite the explosive charge and to be impinged by the firing pins, and a high explosive charge 75 surrounding the casing.

4. In a fuse, a body having an internal bore, a hammer consisting of a body having a transversely disposed channel, guards slideable therein, means for yieldingly pressing the guards toward the center of the hammer, a pin slideable in the hammer, means on the pin engaged by the guards for holding the said pin normally outward, firing pins carried by the hammer, a member against which the pin abuts for preventing movement of the hammer under normal conditions, a casing having its walls grooved for 80 weakening the said walls within the body of the fuse, said casing having an explosive charge therein, caps in position to ignite the explosive charge and to be impinged by the firing pins, and a high explosive charge 85 surrounding the casing.

5. In a fuse, a body having an internal bore, a hammer consisting of a body having a transversely disposed channel, guards slideable therein, means for yieldingly pressing the guards toward the center of the hammer, a pin slideable in the hammer, means on the pin engaged by the guards for holding the said pin normally outward, firing pins carried by the hammer, a member against which the pin abuts for preventing movement of the hammer under normal conditions, a casing having its walls grooved for 90 weakening the said walls within the body of the fuse, said casing having an explosive charge therein, caps in position to ignite the explosive charge and to be impinged by the firing pins, and a high explosive charge 95 surrounding the casing.

6. In a fuse, a body having an internal bore, a hammer consisting of a body having a transversely disposed channel, guards slideable therein, means for yieldingly pressing the guards toward the center of the hammer, a pin slideable in the hammer, means on the pin engaged by the guards for holding the said pin normally outward, firing pins carried by the hammer, a member against which the pin abuts for preventing movement of the hammer under normal conditions, a casing within the body of the fuse, said casing having an explosive charge therein, caps in position to 100 ignite the explosive charge and to be impinged by the firing pins, a high explosive charge surrounding the casing, an expanding member within the casing, a member adapted to travel for expanding the said member, and means for imparting the force of the first mentioned explosive charge to the said 105 means for expanding the member.

7. In a fuse, a body having an internal bore, a hammer consisting of a body having a transversely disposed channel, guards slideable therein, means for yieldingly pressing the guards toward the center of the hammer, a pin slideable in the hammer, means on the pin engaged by the guards for holding the said pin normally outward, firing pins carried by the hammer, a member against which the pin abuts for preventing movement of the hammer under normal conditions, a casing within the body of the fuse, said casing having an explosive charge therein, caps in position to 110 ignite the explosive charge and to be impinged by the firing pins, a high explosive charge surrounding the casing, an expanding member within the casing, a member adapted to travel for expanding the said member, and means for imparting the force of the first mentioned explosive charge to the said 115 means for expanding the member.

8. In a fuse, a body having an internal bore, a hammer consisting of a body having a transversely disposed channel, guards slideable therein, means for yieldingly pressing the guards toward the center of the hammer, a pin slideable in the hammer, means on the pin engaged by the guards for holding the said pin normally outward, firing pins carried by the hammer, a member against which the pin abuts for preventing movement of the hammer under normal conditions, a casing within the body of the fuse, said casing having an explosive charge therein, caps in position to 120 ignite the explosive charge and to be impinged by the firing pins, a high explosive charge surrounding the casing, an expanding member within the casing, a member adapted to travel for expanding the said member, and means for imparting the force of the first mentioned explosive charge to the said 125 means for expanding the member.

pinged by the firing pins, a high explosive charge surrounding the casing, an expanding member within the casing, a member adapted to travel for expanding the said member, means for imparting the force of the first mentioned explosive charge to the said means for expanding the member, said expanding member having beveled surfaces

engaged by the means for expanding it, and a slot for weakening the said member.

In witness whereof I hereunto affix my signature in the presence of two witnesses.

DOMINGO A. PISTORIO. 10
